GLOBE AND SUPPORT

Edward J. Pohlman, Chicago, Ill., assignor to
Rand, McNally & Company, Chicago, Ill., a cor-
poration of Illinois

Application March 25, 1935, Serial No. 12,943

5 Claims. (Cl. 35—46)

This invention relates to a globe and support therefor, and more particularly to a support permitting ready movement from place to place.

One feature of this invention is that it provides a convenient support for a globe; another feature of this invention is that it enables the globe and support to be moved readily from place to place; yet another feature of this invention is that the support may be moved with very little physical effort; other features and advantages of this invention will be apparent from the following specification and drawings, in which—

Figure 1 illustrates the globe and support being moved; Fig. 2 is a detailed sectional view of the socket; Fig. 3 is a view of the base along the line 3 of Fig. 1; Fig. 4 is a view of another embodiment of this invention; Fig. 5 is a view along the line 5 of Fig. 4; and Fig. 6 is a sectional view on the line 6 of Fig. 4.

It has been quite common to mount globes in supports having a base adapted to stand upon the floor of the room in which the globe is being used. In order to provide a firm support, however, it is necessary that the base have a large diameter. This is generally achieved by having a base which comprises three or more legs extending outwardly from the central support. The entire assembly is usually rather heavy and cumbersome, and thus difficult for a teacher or pupil, for example, to move from place to place in the room, or even to another room. Casters have been used on the bases in order to assist in movement. Such casters, however, become rusted or stuck in one position after long disuse, and thus prevent easy guiding of the support when it is being moved. Such casters, moreover, are of small diameter, and thus are very difficult to move over along slight projection in the floor, as a threshold or the edge of a rug.

This invention provides a globe support and base which obviate these difficulties. The base member is made in the form of a wheel, and is of sufficient weight and diameter not only to serve as a firm base, but also to act as a counterweight when the support is inclined from the vertical position. The base, or wheel member, is also provided with a peripheral traction member or tire which prevents the base from slipping out from under the support when the support is inclined. It will be readily apparent that when the support is inclined, the base serves as a wheel member and counterweight, permitting ready movement from place to place with little physical effort and with no interference from intervening projections above the floor level.

In the particular embodiment of this invention illustrated in Figs. 1, 2 and 3, the base wheel member is indicated by the reference numeral 10. The base member has centrally mounted therein, and perpendicular thereto, a support or standard 11, here shown as a pipe or tube. The support receives therein an extension member or rod 12, which extension member may be locked at any desired point, as by the wing nut 13. The extension member has mounted thereon a socket 14, which socket is formed integral with the yoke 15. The yoke has thereon U-shaped supporting members 16 which yieldingly engage an annulus 17, which annulus has a globe 18 mounted therein on its polar axis 19. The reference numeral 20 indicates a person in the act of moving the globe and support, showing the hand 21 grasping the annulus and the hand 22 grasping the yoke of the support.

Referring more particularly to Fig. 2, the socket 14 is shown as having a recess or opening 23 which receives the extension member 12. The extension member 12 has near the upper end thereof a circumferential recess or slot 24, which slot is adapted to receive the end of a plunger 25. The plunger is yieldingly mounted in a housing 26, which housing is mounted in the socket 14, and has an exterior handle portion 27. The construction of the socket forms a firm support and connection between the yoke and the extension member, and yet permits ready rotation of the one with respect to the other. When it is desired to disassemble the support, the socket may be removed from the extension member by pulling out the handle portion 27 sufficiently to disengage the plunger 25 from the slot 24.

Referring more particularly to Fig. 3, the base member 10 is shown downwardly turned towards its edge 28. The member is provided, near its edge, with depressions or grooves 29 and 30, which grooves are adapted to receive the ends of a split tube or tire 31. The base 10 may be of any desired heavy material as iron, which material is prevented from contacting the floor by the frictional member or tire 31. It will be noted that the tire 31 is so arranged as to engage the floor in whatever position the base member 10 may be.

Due to its diameter and weight, the wheel member 10 forms a substantial base for the support 11 and maintains the globe and support in an upright position during normal usage. When it is desired to move the globe, the entire support is inclined from the vertical, substantially as illustrated in Fig. 1. The member 10 now serves

a dual function, serving as a counterweight to balance the weight of the globe and yoke, and as a wheel adapted to roll along the floor when a forward force is applied by the person 20. The 5 frictional member 31 prevents slipping of the wheel member 10, and insures that it will follow the forward course desired by the person moving the globe. In the embodiment illustrated here, the rotation point between the globe and the 10 wheel member is at the connection between the extension member 12 and the socket 14. It may be thus seen that the globe, annulus or yoke 15 may be grasped when the globe is being moved, since all of these parts may be held while the 15 wheel member, support and extension rod rotate with respect thereto.

In the embodiment of this invention illustrated in Figs. 4, 5 and 6, the support 11 and the extension member 12 do not rotate with respect to 20 the yoke 15 and globe 18. The standard 11 is here shown as provided with a handle 32 which may be grasped by the hand 22 when the globe and support are being moved. The base member 10 is, in this embodiment, rotatably mounted 25 with respect to the standard 11. This may be accomplished, for example, by providing the base member 10 with an opening 33 adapted to slidably receive the support 11 and by mounting collars 34 and 35 upon the support 11 above and 30 below the opening 33.

In this embodiment the base 10 is illustrated as having at its edge a rim or socket 36, which socket is substantially semi-circular in cross section. This socket is adapted to receive a frictional 35 member or rubber tire 37 having therein a tension member or wire 38, which tension member holds the tire in place in the socket. It will be noted that the edge 39 of the socket does not touch the floor when the base is in its normal position, and that the exterior edge 40 is sufficiently removed 40 from the floor not to contact the same even when the base is inclined at a considerable angle. It will be thus seen that the tire 37, like that illustrated in Fig. 3, forms a frictional contact 45 with the floor in any desired position of the base member 10.

The standard of the support disclosed herein is an elevated one. That is, it reaches substantially to, or higher than, the waist of a normal adult, so that when the base of the support is 50 resting on the floor, the globe may be conveniently examined without sitting down or stooping. The base, standard, yoke and annulus are preferably made of metal and thus the entire combination is too heavy to be conveniently picked up 55 and carried when it is desired to move it from place to place. It is understood, however, that the yoke and annulus, for example, may be made of any sturdy material, i. e., material capable of 60 withstanding the rough handling which is a necessary element of the force used on them in moving the globe and support from place to place.

While I have shown and described certain 65 embodiments of my invention, it is to be understood

that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new, and desire to secure by Letters Patent, is:

1. A support for a globe, said support being of considerable height and including a heavy base wheel member, rotatably mounted with respect to the globe, said member forming a stationary base for said support when said support is in an upright position and forming a rolling wheel for said support when said support is inclined at a considerable angle.

2. A support for a globe, said support being of considerable height and including a heavy base 20 wheel member, rotatably mounted with respect to the globe, said member forming a stationary base for said support when said support is in an upright position and forming a rolling wheel for said support when said support is inclined at an 25 angle of substantially 45°, said member being provided with a resilient peripheral frictional member.

3. A support for an elevated standard adapted to support a yoke and sturdy annulus having a 30 sturdy globe revolvably mounted therein, including; a base member mounted on the bottom of said standard, said member and standard being rotatable with respect to said yoke and being of sufficient weight and diameter to form a stationary base for said standard when said standard is in an upright position and to act as a counterweight and rolling wheel when said standard is inclined at an angle of substantially 45°; and a 35 resilient frictional member mounted on the periphery of the first mentioned member to prevent side-slipping when using the wheel in moving the globe from place to place.

4. A support for a standard of considerable height adapted to support a yoke and annulus 40 having a globe revolvably mounted therein, said globe and annulus being of sufficient weight and strength to withstand rough handling, including; a base wheel member revolvably supporting said standard, said member being of sufficient weight 50 and diameter to furnish a suitable stationary base for the globe when said standard is in an upright position and to act as a counterweight and rolling wheel when said standard is inclined at an angle of substantially 45°, said member 55 also being provided with a resilient peripheral frictional member to prevent side-slipping when using the wheel in moving the globe from place to place.

5. Apparatus of the character claimed in claim 60 3, wherein said standard includes a telescoping extensible portion.

EDWARD J. POHLMAN.
